(57) **CLAIM**

I claim the ornamental design for a protective bag for dress uniform hats, as shown and described.

DESCRIPTION

FIG. 1 is a perspective view of a protective bag for dress uniform hats, illustrated in an open position, showing my new design;

FIG. 2 is a perspective view thereof, illustrated in a closed position;

FIG. 3 is a front elevational view of FIG. 2;

FIG. 4 is a rear elevational view of FIG. 2;

FIG. 5 is a left-side elevational view of FIG. 2, the right-side elevational view being a mirror image thereof;

FIG. 6 is a top plan view of FIG. 2; and,

FIG. 7 is a bottom plan view of FIG. 2.

The broken lines showing a hat in FIG. 1 are included for the purpose of illustrating the invention in use, and form no part of the claimed design.
